UNITED STATES PATENT OFFICE.

FRANK ARBTER, OF CHICAGO HEIGHTS, ILLINOIS.

WINDOW CONSTRUCTION.

1,273,309.

Specification of Letters Patent.

Patented July 23, 1918.

Application filed December 27, 1917. Serial No. 209,015.

To all whom it may concern:

Be it known that I, FRANK ARBTER, a subject of the Emperor of Austria, residing at Chicago Heights, in the county of Cook and State of Illinois, have invented certain new and useful Improvements in Window Construction, of which the following is a specification.

My invention relates to window construction and has for its primary object the provision of an improved construction for window casements, window-sash and the like, by means of which the glass is securely held in position and by means of which the removal of a broken pane and the insertion of a new one are simple and rapid operations. A further object is the provision of a construction having the above features in combination with great strength.

Other objects and advantages of my invention will become apparent from the following description taken in conjunction with the accompanying drawings which illustrate the preferred embodiment of the invention and form a part of this specification.

In the drawings—

Figure 1 is an interior front elevation of the upper portion of a window casement embodying the present invention;

Fig. 2 is a section taken on line 2—2 of Fig. 1 and looking in the direction indicated by the arrows;

Fig. 3 is a section taken on line 3—3 of Fig. 1 and looking in the direction indicated by the arrows;

Fig. 4 is an inverted view in perspective of a channel-shaped spring metal rib employed across the top of the casement;

Fig. 5 is a view in perspective of a similarly shaped rib employed on the sides of the casement;

Fig. 6 is an interior front elevation of the ribs shown in Figs. 4 and 5, illustrating these ribs in their connected relation; and Figs. 7 and 8 are respectively a side elevation and a front end elevation of a spreader employed in attaching and removing the ribs of my invention.

Reference numeral 10 indicates a steel shape employed in forming the vertical sides of the casement frame and 11 a steel shape preferably T shaped in cross-section which I employ across the top and bottom of the casement. Each of the shapes 10 and 11 is

provided with an exteriorly extending flange 12. Each of the flanges 12 carries a plurality of undercut studs 13 projecting inwardly of the casement and all placed in a common vertical plane spaced sufficiently from the base 10 and 11 of the shapes to accommodate a pane of glass 14 and a body of putty 15 on each side of the glass. At 16 is indicated a spring metal channel-shaped rib, substantially U-shaped in cross-section, and inturned along the extremity of its side webs as at 17; this rib being the one employed at the top and bottom of the casement. Reference numeral 18 indicates a channel-shaped spring metal rib employed in the sides of the window casement and which is a duplicate of the rib 16 as far as the cross-section is concerned. Each of the ribs 16 and 18 is slotted as at 19 substantially opposite one of the studs 13 and is preferably slightly notched at its center, as at 21, to accommodate the shank 22 of a spreader 23, the spreader being inserted into the transverse web of either rib and turned within the rib, as shown in dotted lines in Fig. 3 in order to expand the free edges of the side webs of the rib sufficiently to permit the inturned portions 17 to pass over the cross diameter of the projecting studs 13.

In fitting together the ribs 16 and 18 the ends of the rib 16 at top and bottom of the casement are split and a tongue 22^a downbent to fit within the open ends of the ribs 18, as indicated in Fig. 6. In order that the ribs 18 may be removed from the casement without distortion the indent portions 17 of the free edges of the side webs of the ribs 18 are cut away, as at 23^a in Figs. 5 and 6, at the upper and lower ends of both side ribs.

In assembling a window in the casement of the present invention, the studs 13 being in place in the flanges 12, the operator inserts the header 23 in each slot 19 and by turning the header within the rib spreads the portions 17 apart sufficiently to permit the side webs of each rib to snap over and bind beneath the undercut head of each stud 13, as best shown in Figs. 2 and 3. In this operation the upper and lower ribs 16 are first set in place, following which the side ribs 18 are positioned. If desired, the glass 14 and a portion of the body of putty 15 may be positioned in the shapes 10 and 11 110

before the ribs 16 and 18 are set, and following the setting of the ribs that portion of the body of putty standing between the glass and the ribs may be worked into place 5 by means of a putty knife in the ordinary manner. In removing broken glass from the casement the broken portions of glass and the dried putty about their edges are scraped from the recess formed between the 10 shapes 10 and 11 and the ribs 16 and 18, following which by use of the spreader 23, the ribs are readily removed from studs 13. A portion of the putty body and the new glass are positioned in the shapes 10 and 11, following which the ribs are set and the remainder of the putty worked in, as above described.

It will be seen that owing to the spring character of the metal composing the ribs, 20 these ribs are securely held upon the studs 13, and the glazing of the window is rendered an extremely rapid and easy operation because of the readiness with which the ribs may be attached and removed. Preferably 25 the tongues 22^a are of sufficient width to fit snugly within the ribs 18, whereby it will be seen that the true alinement will always be maintained with ribs 16 and 18, regardless of any slight distortion in the manufacture 30 of either of these ribs.

While I have illustrated the preferred embodiment of my invention, it will be obvious that one skilled in the art may make modifications thereof without departing from the 35 spirit of the invention. I wish, therefore, not to be restricted to the precise embodiment shown except in so far as the same is limited in the appended claims.

I claim:

40 1. In a window casing, the combination with undercut studs, of glass-holding ribs adapted to snap over said studs, each of said ribs comprising a spring metal channel having the free edges of its side webs bent toward each other, said channels having their

bottom webs slotted at a point opposite each of the studs for insertion of a tool.

2. In a window casing; the combination with a frame; of an upper glass-holding rib comprising a channel member split at its 50 ends, and a tongue bent outwardly of said channel at the split portion of each end; and channel-shaped side ribs each abutting at its upper end against the bottom surface of said upper rib; each of said tongues fitting snugly between the side webs of its respective side rib.

3. In a window casing; the combination with a frame; of undercut studs projecting inwardly thereof; upper and lower glass 60 holding ribs comprising metal channels having out-turned, resilient side webs the free edges of which are indent for engagement with the studs; side ribs abutting at their ends against the opposed inner surfaces of 65 said upper and lower ribs and similar in cross-section to said upper and lower ribs; and a tongue formed at each end of each upper and lower rib and projecting into and closely fitting the channel of each side rib. 70

4. In a window casing; the combination with a frame; of undercut studs projecting inwardly thereof; upper and lower glass-holding ribs comprising metal channels having out-turned, resilient side webs the free 75 edges of which are indent for engagement with the studs; side ribs abutting at their ends against the opposed inner surfaces of said upper and lower ribs and similar in cross-section to said upper and lower ribs; and a tongue formed at each end of each upper and lower rib and projecting into and closely fitting the channel of each side rib; the indent portion of the free edge of each side web of the side ribs being cut away 80 opposite each of said upper and lower rib tongues.

In testimony whereof I affix my signature.

FRANK ARBTER.
